UNITED STATES PATENT OFFICE

154,102

DESIGN FOR A SPECTACLE FRAME

Mafalda Davis, New York, N. Y.

Application July 25, 1947, Serial No. 140,501

Term of patent 7 years

(Cl. D57—1)

To all whom it may concern:

Be it known that I, Mafalda Davis, a citizen of the United States, residing at New York, in the county of New York and State of New York, have invented a new, original, and ornamental Design for a Spectacle Frame, of which the following is a specification, reference being had to the accompanying drawing, forming part thereof.

In the drawing:

Fig. 1 is a top view of a spectacle frame showing my new design; and

Fig. 2 is a front view thereof.

I claim:

The ornamental design for a spectacle frame, as shown.

MAFALDA DAVIS.
